SANITARY PUMP

David F. Thomas, Minneapolis, Minn., assignor
to Waterous Company, St. Paul, Minn., a corporation of Minnesota

Application May 17, 1948, Serial No. 27,521

9 Claims. (Cl. 103—126)

1

My invention relates to an improvement in sanitary pump of a type which may be used for pumping foodstuffs and the like.

In recent years it has become increasingly desirable to handle various pulpy, liquid, and semi-liquid materials by the use of pumping systems. Rather than to convey liquid or semi-liquid foodstuffs from place to place, the material has been pumped from one place to another by means of suitable pumping equipment. In order to accomplish this result in a sanitary manner, the pumps used for the purpose must be designed so that they can be easily taken apart and cleaned after intervals of use. Thus in such structures, it is desirable to provide pumps which can be easily taken apart and reassembled for cleaning purposes.

The object of the present invention lies in the provision of a pump which may be easily taken apart and cleaned when desired. My pump includes a gear compartment which is designed to rotatably support a pair of hollow elongated sleeves. These sleeves are driven in unison by a suitable drive gear arrangement. The sleeves are arranged to support a pair of impeller supporting shafts. These shafts are provided with impellers at one end thereof and fastening means at the other end thereof, and thus may be removed in their entirety when desired for cleaning and sterilizing purposes.

A feature of the present invention lies in the provision of an impeller compartment which is split in such a manner that the pump chamber is partially formed in each of two removable wall sections. As a result neither section is provided with an extremely deep cavity forming a part of the pump chamber as the chamber is divided between the two wall sections.

A feature of the present invention lies in the provision of a gear chamber which may be entirely sealed and which acts to drive two parallel rotatable sleeves. As a result the impellers may be provided with integral impeller shafts which may be removed or withdrawn from the gear chamber without danger of having these shafts contaminated by grease or oil.

A feature of the present invention resides in the fact that the impellers may be integrally connected to the drive shaft. As a result one side of each impeller is not subject to leakage as it leads only to a recess in the pump chamber wall and is thus entirely sealed. As a result it is only necessary to seal one side of the impeller against leakage.

An added feature of the present invention lies in the provision of a sanitary pump having seg-

2

ment shaped impellers which project beyond the end of the supporting shaft. In the past it has been common practice to support the impellers or rotor in a direction to encircle a part of the supporting shaft. In the present case, the impellers project beyond the end of the supporting shaft and may encircle a fixed portion of the housing end wall.

An added feature of the present invention lies in the specific drive device by means of which the rotors or impellers are rotated. The impeller shafts are rotated in unison with the sleeves into which they are inserted. The sleeves are rotated by intermeshing gears so that the rotors will operate in unison and in timed relation. The intermeshing gears are operated by a drive gear mounted upon a drive shaft for engaging one of the gears on one of the sleeves.

An added feature of the present invention lies in the small number of parts which must be removed in taking the pump apart for cleaning or sterilizing. The six wing nuts supporting the pumping chamber housing walls and the two nuts holding the impellers in place must be removed. The two housing walls may then be freely removed as well as the combined impellers and drive shafts. Seals are interposed between the rear side of each impeller and one of the housing walls, and this sealing means should preferably be removed during the cleaning operation. Thus an extremely small number of parts must be removed for the cleaning operation.

These and other objects and novel features of my invention will be more clearly and fully set forth in the following specification and claims.

35 In the drawings forming a part of my specification:

Figure 1 is an end elevational view of the pump in assembled form with head, impellers, housing, and seals removed.

40 Figure 2 is a view of the pump with the forward body wall thereof removed.

Figure 3 is a top plan view partly in section along the line 3—3 of Figure 1.

45 Figure 4 is a vertical sectional view through the pump.

The sanitary pump A illustrated in the drawings is most completely illustrated in Figure 4 of the drawings. It will be noted that the pump A includes a forward portion illustrated in general by the numeral 10 and including a pump chamber, impellers, and the like. The pump also includes a rear section 11 which forms a gear chamber and encloses the gears and impeller shaft supports. The gear chamber 11 is supported by a longitudinally extending web 12 and

a transversely extending web 13 to a horizontal supporting plate 14 which may be bolted or otherwise affixed to a supporting platform or the like.

The gear housing 11 is rounded at its rear end and includes an integral end closure wall 15. The wall 15 is provided with a pair of parallel apertures 16 and 17 extending partially therethrough and communicating with larger diameter apertures 19 and 20 extending the remainder of the distance therethrough. A ball bearing 21 is supported in the large diameter portion 19 of one aperture and a similar ball bearing 22 is supported in the large diameter portion 20 of the other aperture.

The other end of the gear housing 11 is provided with an inwardly directed flange 23 through which a pair of bearing cartridges 24 and 25 extend. The bearing cartridges 24 and 25 are generally cylindrical in shape but are cut away along their adjacent sides as indicated at 26 so that the two cartridges may fit closely together. A pair of ball bearings 27 and 29 are provided within the cartridge 24 and a similar pair of bearings 30 and 31 are provided within the cartridge 25. The cartridge 24 is provided with an inwardly extending flange 32 against which the bearings 27 and 29 may engage. The cartridge 25 is provided with a similar inwardly extending flange 33 against which the bearings 30 and 31 may engage. A removable ring-shaped retaining plate 34 is secured to the cartridge 24 to lock the bearings 27 and 29 in place. A similar retainer ring 35 is removably attached to the bearing cartridge 25 to lock the bearings 30 and 31 in place therein.

An elongated hollow sleeve or mandrel 36 is rotatably supported by the bearings 27 and 29 and the aligned bearing 21 in the rear wall 15. A sleeve 36 is provided with an enlarged diameter end 37 against which the bearings 27 and 29 may engage to hold the sleeve from axial movement. The sleeve is externally threaded at 38 to accommodate a lock nut 40. A spacing sleeve 41 encircles the sleeve 36 adjacent the bearing 29 to hold this bearing spaced from a pilot gear 42. The nut 40 engages against the pilot gear 42 to hold the pilot gear and bearings 27 and 29 in fixed relation upon the sleeve. A lock washer 43 holds the nut 40 from accidental disengagement.

A similar hollow sleeve or mandrel 44 is supported by the bearings 30 and 31 and the aligned bearing 22 in the rear wall 15. The sleeve 44 is provided with a large diameter end 45 against which the bearing 30 may engage. A spacing sleeve 46 encircles the sleeve 44 between the bearing 31 and the pilot gear 47. The pilot gear 47 is opposite and in mesh with the pilot gear 42. A nut 49 is threadably engaged on the sleeve 44 to hold the pilot gear 47 and the bearings 30 and 31 in fixed relation to the sleeve. A lock washer 50 prevents accidental disengagement of the nut 49.

The bearing cartridges and retainers are held in place by means of a gear compartment closure wall 51. This closure wall is provided with spaced apertures 52 and 53 through which the enlarged diameter ends 37 and 45 of the sleeves 36 and 44 may extend. Cap screws 54 secure the cartridges 24 and 25 to the closure plate 51. The closure plate 51 is secured to the end of the gear casing 11 by means of cap screws or countersunk bolts which are off-set from the particular sections illustrated and which are indicated in Figure 1 by the numeral 55.

In order to entirely close the gear compart-

ment, a seal 56 encircles the large diameter portion 37 of the sleeve 36 and a similar seal 57 encircles the large diameter portion 45 of the sleeve 44. These seals 56 and 57 fit between the sleeves 36 and 44 and the end closure wall 51 to seal this end of the gear casing. Seals 58 and 60 are interposed between the other ends of the sleeves 36 and 44 and the walls of apertures 16 and 17 so as to form a seal at the other extremity of the gear housing externally of the ball bearings 21 and 22.

In order to drive the sleeves 36 and 44 in unison I provide a drive shaft 61 which extends into the rear end of the gear case 11 as illustrated in Figure 3 of the drawings. The shaft 61 is slightly below the center between the gears 42 and 47 and is provided with a pinion 62 which engages the lower gear 47. The shaft 61 is supported by a ball bearing 63 and a ball bearing 64 mounted in the longitudinally extending aperture 65 in the gear case. A spacing sleeve 66 is interposed between the ball bearing 64 and the bearing 63 and is held in proper spaced relation by a set screw 67. A sealing ring 69 seals the bearing 64.

The closure wall 51 is provided with a forwardly extending flange 70 which extends the major portion of the periphery of this wall but which is discontinued at points spaced from the central spacing boss 71 at the lower edge of the housing so that the space forwardly of the closure wall 51 is open to atmosphere. Thus any grease or oil leaking from the gear case may drain from the casing through the open bottom end thereof at this point and any material being pumped, leaking from the pump chambers 55 may also drain from the casing at this point. In other words, the open space on opposite sides of the center spacing boss 71 acts to separate the pump chamber from the gear chamber and to allow any material leaking from either chamber to drain from the casing.

The pump body 72 is provided with a pair of intersecting impeller chambers 77 and 79 therein, the outline of which is best illustrated in Figure 2 of the drawings, the section of which is best illustrated in Figure 4 of the drawings. These intersecting impeller chambers 77 and 79 communicate with smaller diameter openings 80 and 81 respectively. These openings 80 and 81 are spaced and are designed to accommodate the impeller supporting discs or cylinder portions of the impeller shaft supporting the impellers themselves. The apertures 80 and 81 terminate in rabbeted double shoulders 82 and 83 for accommodating a sealing element as will be later described.

The intersecting impeller chambers 77 and 79 are continued in the pump casing head 73, this head being provided with intersecting ring shaped apertures 84 and 85 which are aligned with the apertures 77 and 79. The head 73 is likewise provided with a rearwardly projecting central boss concentric with each of the chambers or apertures 84 and 85. These bosses 86 and 87 are designed to extend within the impellers and to complete the pump chambers. In other words, the pumping chambers extend between the central bosses 86 and 87 and the chamber forming recesses 77 and 79, and their extensions 84 and 85.

The impellers are integrally connected to impeller shafts 91 and 92 having a proper outside diameter to fit through the sleeves 36 and 44 respectively. The sleeves are provided with large diameter aperture portions 93 and 94 respectively which snugly fit about a large diameter portion

95 or 96 of the impeller shafts 91 and 92. Second snugly fitting bearing portions are indicated at 89 and 90. The major portion of the length of the shafts 91 and 92 are of somewhat smaller diameter as indicated in Figure 4 to fit freely within the smaller diameter apertures 97 and 99 of the sleeves 36 and 44. The ends of these impeller shafts are threaded as indicated at 100 and 101 respectively to accommodate fastening nuts 102 and 103. These nuts hold the impellers and impeller shafts in place within the hollow shafts or sleeves 36 and 44. The impellers include hubs 104 and 105 respectively which engage against the forward ends of the hollow shafts 36 and 44. As illustrated these hubs 104 and 105 interlock with the forward ends of the sleeves 36 and 44 so as to rotate in unison therewith. The hubs 104 and 105 are provided with flattened sides such as 106 and the sleeves 36 and 44 are notched at their forward ends and thus provided with forwardly projecting shoulders 107 which interlock into these flattened sides 106. As a result the sleeves rotate in unison with the impellers and act to drive the same. The impellers are arranged to travel in intersecting paths and to pump fluid or semi-fluid material from the inlet to the outlet. The entire impeller, hub and shank assemblies may be termed impeller units.

As indicated in the drawings an inlet port 109 and an outlet port 110 are provided on opposite sides of the casing extending through the pump body 72. These ports 109 and 110 are provided within projecting bosses which may be externally threaded to accommodate a suitable fitting. Either port may serve as the inlet and either port may serve as the outlet depending upon the direction of rotation of the impellers.

A seal is provided between the impeller hubs 104 and 105 and the wall or cavity within the pump body 74. A ring shaped sealing member 111 encircles the hub 104 and is held in place by a sliding engagement between the sleeve and the rabbeted wall 82 of the pump body 72. A large diameter portion 112 on the ring 111 fits within the cylindrical bore 113 of the body wall and a smaller diameter portion 114 of the sleeve 111 fits within the smaller diameter opening 115 of the body wall. An O ring 116 is provided between the two different diameter portions of the ring and the two different diameter portions of the wall. A spring 117 is interposed between the base of the larger diameter portion 80 of the body wall and an integral flange 119 on the ring 111. This spring urges the sealing ring against the end of the hub, thus forming an effective seal between the ring 111 and the hub. The O ring 116 acts as a seal between the ring 111 and the wall of the body 72. A similar seal encircles the hub 105. The ring 120 freely encircles the hub 105 and is provided with a rabbeted edge which cooperates with the rabbeted edge 83 of the body 72 to accommodate an O ring 121 between the ring and the body wall to act as a seal therebetween. A spring 122 encircles the ring 120 and is interposed between the body wall and a projecting flange 123 on the ring acting to urge the ring against the end surface of the impeller hub to act as a seal therebetween.

The advantages of my construction are believed obvious from the foregoing description. Any fluid or semi-fluid material may be drawn into the pump casing through one portion such as 109 and forced from the other port such as 110. The impellers are rotated in unison with their supporting sleeves or hollow shafts 36 and 75

44. When it is desired to clean the pump, it is only necessary to remove the wing nuts 76 in order to remove the pump head 73. By removing the nuts 102 and 103 at the opposite end of the shaft the impellers and their integral shafts may be removed from the pump. When the impellers are removed the pump body 72 may be removed from the studs 75. The sealing elements which are interposed between the pump impellers and the pump body may then be removed and cleaned if desired. As a result all of the parts forming a part of the pump chamber may be easily and quickly removed after removal of the six wing nuts 76 and the two shaft nuts 102 and 103.

15 After the various parts have been entirely washed or sterilized the seals may be inserted into the body portion 72 of the pump and this body portion may be placed over the studs 73. The impellers may be inserted into place and secured in proper rotative relation by the nuts 102 and 103. The head 73 may then be replaced and the pump is in readiness for operation.

20 It will be seen that all of the parts of my pump may be easily cleaned as there are no deep recesses which are inaccessible for cleaning purposes. By forming the pump chamber partially in the pump body and forwardly in the head, the depth of the recesses in which the impeller is recessed is decreased considerably. The impeller shafts are removable with the impellers and the nuts holding the impellers in place are at the opposite end of the apparatus from the pump chamber so that there are no threads within the pumping chamber or near this chamber which might become contaminated because of the difficulty experienced in cleaning them. The hollow shafts which act as the impeller supports do not extend into the pump chambers and therefore need not be removed for cleaning purposes. The ends of these hollow shafts 36 and 44 terminate within the open area between the gear case and the pump chamber portions of the structure which area is open to atmosphere and therefore is not in a portion of the pumping chamber. At the same time a proper alignment between the impellers and the casing is at all times assured by the structure.

25 30 35 40 45 50 55 60 65 70 75 In accordance with the patent statutes, I have described the principles of construction and operation of my sanitary pump and while I have endeavored to set forth the best embodiment thereof, I desire to have it understood that obvious changes may be made within the scope of the following claims without departing from the spirit of my invention.

I claim:

1. A rotary pump including a gear housing, a pair of hollow shafts rotatably supported by said gear housing, a pair of intermeshing gears on said hollow shafts for rotating said hollow shafts in unison, a drive shaft supported parallel to said hollow shafts in said gear casing, a pinion on said drive shaft engageable with one of said intermeshing gears, a pair of impellers designed for rotation in intersecting paths, and shafts on said impellers removably supported by said hollow shafts and rotatable therewith.

2. A rotary pump including a gear housing, a pump housing removably connected to said gear housing, a pair of impellers rotatable about intersecting paths, each impeller including an arcuate segment with curved ends, impeller shafts secured to said impellers and extending into said gear housing, an impeller hub on each of said shafts at one extreme end thereof, said impellers

being connected to said hub to project beyond the end of said shaft.

3. The structure described in claim 2 in which the pump housing comprises a pump body and a pump head having an impeller chamber therein comprising two intersecting ring shaped chamber portions enclosed by encircling walls, said walls being partially formed by both said body and said head.

4. The structure described in claim 2 in which the pump housing includes a body within which said impellers rotate and a head including a boss concentric with, and extending axially toward each said shaft within said impellers.

5. An impeller shaft for a rotary pump including an impeller hub at one end of the shaft, impellers integrally secured to said hub and projecting beyond the end of the shaft, said impellers comprising arcuate segments having curved ends, and threads at the opposite end of said shaft.

6. A pump comprising a pump housing including an impeller chamber, said impeller chamber including a pair of intersecting ring shaped chamber sections the housing forming encircling peripheral walls, said housing including a body portion and a removable cover portion, the cover portion and body portion being separated between the ends of said encircling walls defining the periphery of said chamber.

7. The structure described in claim 6 and including a pair of cylindrical bosses on said cover portion forming the inner walls of said intersecting ring shaped chambers.

8. A pump construction including a gear casing, a pair of parallel hollow shafts mounted on said gear casing, means connecting said shafts for causing rotation thereof in unison, a pair of impeller units removably secured to said shafts, said impeller units including elongated shanks designed to extend through said hollow shafts, and impellers supported upon one end of each of said shanks and designed to travel in intersecting paths, impeller hubs on said shanks designed to extend in abutting relation with an end of the corresponding hollow shaft, a notch in the end of each of said hollow shafts, and a projection on each of said impeller hubs engageable

into the notch when said impeller shanks are supported within said hollow shafts, said notches and projections holding the impeller in proper angular relation.

5 9. The structure described in claim 8 and in which the impeller units are interchangeable.

DAVID F. THOMAS.
